UNITED STATES PATENT OFFICE

SIMON DE VAULCHIER, OF NEW YORK, N. Y., ASSIGNOR TO CHAMBERLAIN LABORATORIES, INC., OF DES MOINES, IOWA, A CORPORATION OF IOWA

DESIGN FOR A BOTTLE

Application filed March 24, 1932. Serial No. 43,281. Term of patent 14 years.

To all whom it may concern:

Be it known that I, SIMON DE VAULCHIER, a citizen of the United States, and a resident of New York, in the county and State of New York, have invented a certain new, original, and ornamental Design for a Bottle, of which the following is a specification, reference being had to the accompanying drawing, forming part hereof, in which—

I claim:

The ornamental design for a bottle as shown.

Des Moines, Iowa, December 4, 1931.

SIMON DE VAULCHIER.
